UNITED STATES PATENT OFFICE.

HARRY B. McBEE, OF ST. LOUIS, MISSOURI, ASSIGNOR TO McBEE BINDER COMPANY, OF ATHENS, OHIO.

PRINTING PRESS.

Application filed September 26, 1921. Serial No. 503,317.

To all whom it may concern:

Be it known that I, HARRY B. McBEE, a citizen of the United States, residing at St. Louis, Missouri, have invented a new and useful Improvement in Printing Presses, of which the following is a specification.

My invention relates to the printing art and has for its object to produce a simple, efficient, durable and practically inexpensive 10 device for receiving an article which is to receive an impression and force a frame, carrying a makeup, against it.

My invention consists of certain details of construction hereinafter set forth, pointed 15 out in my claim and illustrated in the accompanying drawings, in which Figure I shows a perspective view of my device, a portion of the same being broken away; and,

Figure II shows a detail view, in section, 20 of a portion of my device, taken on the line 2—2, in Figure I.

Referring to the accompanying drawings the reference numerals 10 and 11 are used to indicate a pair of vertical standards, 25 hollowed in their central parts to receive the vertically mounted, screw-threaded shafts 12 and 13, respectively. These shafts are journaled in bearings in their respective standards, and at the lower end of each is a 30 beveled gear wheel 14. These standards are, obviously, joined together, and extending between the two is a shaft 15, mounted for rotation in its bearings in each of the standards, said shaft being provided with pinions 35 16, to engage each of the beveled gear wheels 14, and said shaft also projecting beyond one of the standards and having a hand-wheel 17 secured to its end.

A second shaft 18 is mounted between the 40 screw-threaded shafts 12 and 13, by means of screw-threaded bearings 19 and 20, supporting the shaft 18, being threaded on to the shafts 12 and 13. The construction is such that the shafts 12 and 13 rotate, when actuated, within the said bearing thus causing the shaft 18 to move upwardly or downwardly. On the shaft 18 is a depending 45 make-up frame 21, designed to receive and retain the type to form the impression to be received by the book, or other article. Extending between the standards 10 and 11, and

below the make-up frame, is a bed plate 22, which may be likened to a platen of a printing-press, except that the function of the bed plate 22 is simply to receive the article to 55 be printed and is not designed to function in the additional ways necessary for a platen.

The operation of my device is as follows: The article to receive the impression is 60 placed upon the bed plate 22 and the operator then rotates the handwheel 17, thus rotating the shaft 15, carrying the pinions 16, which are in mesh with the beveled gear 65 wheels 14. This simultaneously rotates the screw-threaded shafts 12 and 13, thus causing the shaft 18 carrying the make-up frame to be lowered or raised. The operator lowers the shaft 18, forcing the make-up frame 21, containing the make-up which has been 70 inked by the operator, against the article to receive the impression.

As various kinds of articles are designed to be placed in my device for the receiving of the printing, it is obvious that there must be more or less flexibility in the functioning 75 parts. This flexibility I have provided, for the control of applied pressure has been demonstrated to satisfactorily meet this condition. The operator can apply such pressure as may be needed to force the article being printed to a proper parallel plane with 80 the type-bearing frame.

Having thus described my invention, what I claim and desire to secure by Letters Patent of the United States, is:

In a printing press, a pair of companion standards spaced apart, and a bed plate secured to and extending beyond same; a screw threaded shaft vertically mounted for rotation in each of said standards; means to rotate the said shafts simultaneously; a carrying shaft for a make-up frame mounted between said screw threaded shafts in such manner as to be carried upwardly or downwardly of the rotation of the said shafts; a make-up frame depending from the last mentioned shaft, substantially as shown and described.

HARRY B. McBEE.
